UNITED STATES PATENT OFFICE.

JESS GOFF, OF LOS ANGELES, CALIFORNIA, ASSIGNOR OF ONE-THIRD TO O. R. BARTRAM,
OF LOS ANGELES, CALIFORNIA.

MANHOLE SAFETY CAGE.

Application filed March 21, 1928. Serial No. 263,263.

This invention relates to safety devices, and has for an object the provision of a folding safety cage of the type adapted to be positioned about open manholes to prevent accidents which might result from such open manholes being left unguarded.

Another object is the provision of a safety cage as described, which is composed of a plurality of arcuate, or semi-circular bars pivoted to supporting vertical bars in such a manner that the cage may optionally be extended to operative position with the arcuate bars disposed horizontally or folded flat with the plane of the arcuate bars parallel to and closely adjacent that of the vertical bars so as to occupy a minimum of space when in folded position.

A further object of my invention is to improve upon the device heretofore employed, for the purpose stated, and do so in such a way as to produce a safety cage which is simple and rugged in structure, is inexpensive to manufacture, is capable of being quickly set up in position about a manhole, and which, when once set up, offers a positive guard therefor.

With the foregoing and other objects in view which will be made manifest in the following detailed description and specifically pointed out in the appended claims, reference is had to the accompanying drawings for an illustrative embodiment of the invention, wherein:

Figure 1 is a perspective view of my improved folding safety cage in position upon a manhole.

Fig. 2 is a side elevation of the cage in folded position.

Fig. 3 is a rear elevation of the folded cage of Fig. 2, the direction of view being indicated by the arrow 3 of that figure.

Fig. 4 is a front elevation of the folded cage, the direction of view being indicated by the arrow 4 of Fig. 2.

Fig. 5 is an enlarged, detailed, sectional view, showing the ratcheted bracket for holding the cage in position about the manhole.

In terms of broad inclusion, the safety cage of my invention comprises a plurality of arcuate bars pivotally connected at each end to spaced front and rear vertical bars, permitting the cage to be extended with the arcuate bars disposed horizontally to define an enclosure or to be folded with the arcuate

bars disposed in planes parallel to and closely adjacent the vertical bars, so that the folded cage may occupy a minimum of space.

In greater detail, the present embodiment of my invention comprises a plurality of arcuate or semi-circular bars 6. These bars are arranged in two groups, the concave sides of those of each group facing that of the other group when in extended position so as to define an enclosure. All of the bars 6 of both groups, are pivoted at one end to a rear, vertical bar 7. Each group of bars 6 is provided with a front vertical bar 8, and the other end of each of the arcuate bars 6 of the associated group is pivoted to its front vertical bar 8 for movement about a horizontal axis. For this purpose a strap 9 is associated with the front end of each of the arcuate bars 6, with a pivot pin 11 extending through the ends of the strap 9 and through the front end of the arcuate bar 6. The body of the strap 9 surrounds the associated front vertical bar 8 in such a manner as to provide a rigid, horizontal pivot 80 for the front end of the arcuate bar 6.

The after end of each of the bars 6 is similarly pivoted by a horizontal pivot pin 12, to a strap 13 extending around the rear vertical bar 7. In this instance, however, the straps 13 are loosely mounted upon the rear vertical bar 7, permitting movement of the arcuate bars 6 about vertical axes, as well as about horizontal axes, with the result that the front vertical bars 8 may be moved 90 towards or away from each other.

A strap 15 is associated with each group of arcuate bars 6. Each of the straps 15 includes straight portions 16 rigidly connecting journal portions 17 which surround the associated arcuate bars 6 preferably midway between the ends thereof. The arcuate bars 6 are free to turn within the journal portions 17 which are so spaced by the straight portions 16 that the center portions of the arcuate bars 6 are always the same distance apart, irrespective of whether moved to folded or extended position.

An auxiliary strap 18 extends downwards from the bottom of each of the straps 15 surrounding the lowermost arcuate bar 6, and extends upwards on the other side of the strap 15 to provide a foot for supporting the arcuate bars 6 of the associated group when in extended position.

A gate 21 is provided to close the space between the two front bars 8. In their preferable form, the front bars 8 are tubes permitting the insertion of a bent-over portion 5 or hook 22 into the upper end of one of the front vertical bars 8, as the upper hinge for the gate 21. The lower hinge for the gate 21 is in the form of a strap 23 loosely surrounding the same front vertical bar 8 and 10 fastened adjacent the lower side of the gate 21. A second bent-over portion or hook 24 is provided upon the other side of the gate 21 adjacent its upper edge, this hook 24 being adapted to be inserted into the open end of 15 the other front vertical bar or tube to hold the gate in closed position as clearly shown in Fig. 1.

It is to be understood of course, that all 20 the vertical bars 7 and 8, and the arcuate bars 6, may be made of tubing to produce a relatively light cage which is possessed of all the rigidity and strength necessary to yield the desired protection.

Means for locking the cage in extended position, and means for holding the cage while in extended position about an open manhole, are provided. A pin 26 is secured by means of a chain 27 or its equivalent, to each of the straps 15. These pins are adapted to be 30 inserted through a hole in one of the associated journals 17 into a hole in the arcuate bar 6 supported within that journal. These holes are so positioned that they are brought into register when the arcuate bars are moved to horizontal position, or when the cage is in fully extended position. It may thus be seen that folding of the cage is positively prevented with the removal of the pins 26.

40 A bracket 31 extends inwards from one of the front vertical bars 8, this bracket being rigid with its supporting bar and having a depending foot 32 provided with teeth 33. Another bracket 34 is slidable within 45 a horizontal sleeve 36 which is rigid with the bottom of the rear vertical bar 7. A foot 37 depends from the inner end of the sliding bracket 34 and is provided with teeth 38 similar to the teeth 33 of the other bracket 31. The upper surface of the body 39 of the bracket 34 is provided with a plurality of V-shaped notches 41 adapted to be engaged by a pointed ratchet 42 which is urged 50 downwards by a spring 43 under compression between the top of the ratchet 42 and a pin 44 extending rigidly across the rear vertical bar 7 adjacent the bottom thereof.

An arm 46 is pivoted by means of a horizontal pivot pin 47 adjacent the bottom of 60 one of the front vertical bars 8. This arm 46 is adapted to be pressed downwards to a horizontal position to hold the two front vertical bars 8 in spaced relationship as shown in Fig. 1, and is of such length that 65 when so positioned, there is just room be-

tween the two vertical bars 8 for the reception of the gate 21.

The manner of operating my improved safety cage is substantially as follows:

The arcuate bars 6 are first moved from 70 their folded position to a position substantially horizontal, after which the front vertical bars 8 are separated by pressing the arm 46 downwards to the position shown in Fig. 1. The cage is then positioned over the manhole with the foot 32 of the stationary bracket 31 extending downwards against the inner edge of the rim 49 of the manhole. The other bracket 34 is then adjusted to engage the opposite side of the rim 49 to hold 80 the safety cage in position about the open manhole. The arcuate bars 6 should be locked in extended position by inserting the locking pins 26 through the holes in the journals 17 and associated arcuate bars 6. 85 The door 21 may then be optionally opened or closed as above described.

When it is desired to remove the safety cage from the manhole, the reverse operation may be carried out. After folding the 90 gate 21 inwards and lifting the arm 46, the two vertical bars 8 may be brought together. Then, after removing the locking pins 26, the arcuate bars 6 may be elevated to bring them into planes parallel to and closely adjacent the planes of the vertical bars so that the safety cage may be folded flat to occupy 95 a minimum space.

Various changes in the details of construction may be made without departing from 100 the spirit and scope of the invention as defined by the appended claims.

I claim:

1. A safety cage for a manhole, comprising spaced front and rear vertical bars and 105 a plurality of bars pivotally connected at each end to one of said vertical bars for movement about horizontal axes to optionally fold or extend the cage to operative position.

2. A safety cage for a manhole, comprising spaced front and rear vertical bars, a plurality of arcuate bars pivotally connected at each end to one of said vertical bars for movement about horizontal axes to optionally fold or extend the cage to operative 115 position, and means for locking the arcuate bars in extended position.

3. A safety cage for a manhole, comprising spaced front and rear vertical bars and a 120 plurality of arcuate bars pivotally connected at each end to one of said vertical bars for movement about horizontal axes to optionally fold or extend the cage to operative position, said arcuate bars being disposed upon both sides of said vertical bars to define an 125 enclosure when in extended position.

4. A safety cage for a manhole, comprising spaced front and rear vertical bars, a plurality of arcuate bars pivotally connected 130

- at each end to one of said vertical bars for movement about horizontal axes to optionally fold or extend the cage to operative position, said arcuate bars being disposed upon both sides of said vertical bars to define an enclosure when in extended position, and a strap pivotally connected to all of the arcuate bars of each group to hold them in spaced relationship.
- 5 5. A safety cage for a manhole, comprising spaced front and rear vertical bars, a plurality of arcuate bars pivotally connected at each end to one of said vertical bars for movement about horizontal axes to optionally fold or extend the cage to operative position, said arcuate bars being disposed upon both sides of said vertical bars to define an enclosure when in extended position, a strap pivotally connected to all of the arcuate bars 10 of each group to hold them in spaced relationship, and a pin adapted to be inserted through a hole in each of said straps into a hole in one of the associated arcuate bars to lock the cage in extended position.
- 15 6. A safety cage for a manhole, comprising spaced front and rear vertical bars, a plurality of arcuate bars pivotally connected at each end to one of said vertical bars for movement about horizontal axes to optionally fold or extend the cage to operative position, said arcuate bars being disposed upon both sides of said vertical bars to define an enclosure when in extended position, a strap pivotally connected to all of the arcuate bars 20 of each group to hold them in spaced relationship, a pin adapted to be inserted through a hole in each of said straps into a hole in one of the associated arcuate bars to lock the cage in extended position, and means for holding the cage in position about a manhole.
- 25 7. A safety cage for a manhole, comprising a rear, vertical bar, a pair of spaced front vertical bars and a plurality of arcuate bars pivotable at one end to the rear vertical bar and at the other end to one of the front vertical bars for movement about a horizontal axis to optionally fold or extend the cage to operative position.
- 30 8. A safety cage for a manhole, comprising a rear vertical bar, a pair of spaced front vertical bars, a plurality of arcuate bars pivotable at one end to the rear vertical bar and at the other end to one of the front vertical bars for movement about a horizontal axis to optionally fold or extend the cage to operative position, and a gate pivoted to one of said front vertical bars and adapted to be swung across the space between the vertical bars or to be opened therefrom.
- 35 9. A safety cage for a manhole, comprising a rear vertical bar, a pair of spaced front vertical bars, a plurality of arcuate bars pivotable at one end to the rear vertical bar and at the other end to one of the front vertical bars for movement about a horizontal axis to optionally fold or extend the cage to operative position, and a strap pivoted to one of said front vertical bars and adapted to be swung across the space between the vertical bars or to be opened therefrom.
- 40 10. A safety cage for a manhole, comprising a rear vertical bar, a pair of spaced front vertical bars, a plurality of arcuate bars pivotable at one end to the rear vertical bar and at the other end to one of the front vertical bars for movement about a horizontal axis to optionally fold or extend the cage to operative position, means for locking the arcuate bars in extended position, a gate pivoted to one of said front vertical bars and adapted to be swung across the space between the vertical bars or to be opened therefrom, and means for holding the cage in position about a manhole.
- 45 11. A safety cage for a manhole, comprising a rear vertical bar, a pair of spaced front vertical bars, a plurality of arcuate bars pivotable at one end to the rear vertical bar and at the other end to one of the front vertical bars for movement about a horizontal axis to optionally fold or extend the cage to operative position, and a strap pivotally connected to the center portion of the arcuate bars connected to each front vertical bar to retain the arcuate bars in spaced relationship.
- 50 12. A safety cage for a manhole, comprising a rear vertical bar, a pair of spaced front vertical bars, a plurality of arcuate bars pivotable at one end to the rear vertical bar for movement about vertical and horizontal axes, and at the other end to one of the front vertical bars for movement about vertical axes.
- 55 13. A safety cage for a manhole, comprising a rear vertical bar, a pair of spaced front vertical bars, a plurality of arcuate bars pivotable at one end to the rear vertical bar for movement about vertical and horizontal axes, and at the other end to one of the front vertical bars for movement about vertical axes, and a gate pivoted to one of said front vertical bars and adapted to be swung across the space between the vertical bars or to be opened therefrom.
- 60 14. A safety cage for a manhole, comprising a rear vertical bar, a pair of spaced front vertical bars, a plurality of arcuate bars pivotable at one end to the rear vertical bar for movement about vertical and horizontal axes, and at the other end to one of the front vertical bars for movement about vertical axes, a gate pivoted to one of said front vertical bars and adapted to be swung across the space between the vertical bars or to be opened therefrom, and an arm pivoted adjacent the bottom of one of said front bars and

adapted to extend across the space to the other bar to hold them in spaced relationship.

15. A safety cage for a manhole, comprising a rear vertical bar, a pair of spaced front vertical bars, a plurality of arcuate bars pivoted at one end to the rear vertical bar for movement about vertical and horizontal axes, and at the other end to one of the front vertical bars for movement about vertical axes, a gate pivoted to one of said front vertical bars and adapted to be swung across the space between the vertical bars or to be opened therefrom, an arm pivoted adjacent the bottom of one of said front bars and adapted to extend across the space to the other bar to hold them in spaced relationship, and a bracket carried by each of two of said vertical bars and adapted to engage the edge of said manhole to retain the cage in position thereabout.

16. A safety cage for a manhole, comprising a rear vertical bar, a pair of spaced front

vertical bars, a plurality of arcuate bars pivoted at one end to the rear vertical bar for movement about vertical and horizontal axes, and at the other end to one of the front vertical bars for movement about vertical axes, a gate pivoted to one of said front vertical bars and adapted to be swung across the space between the vertical bars or to be opened therefrom, an arm pivoted adjacent the bottom of one of said front bars and adapted to extend across the space to the other bar to hold them in spaced relationship, a bracket carried by each of two of said vertical bars and adapted to engage the edge of said manhole to retain the cage in position thereabout, one of said brackets being adjustable in respect to its effective length, and ratchet means for holding said adjustable bracket in selected position.

In testimony whereof I have signed my name to this specification.

JESS GOFF.
